[57] **CLAIM**

The ornamental design for a combined bleaching and dyeing textile fabric apparatus for bleaching and dyeing textile fabrics, or the like, as shown and described.

DESCRIPTION

FIG. 1 is a perspective view of the combined bleaching and dyeing textile fabric apparatus, showing my new design, the fabric and containers shown in broken lines are for illustrative purposes only, and forms no part of the claimed design;

FIG. 2 is another perspective view thereof;

FIG. 3 is a front elevational view thereof;

FIG. 4 is a top plan view thereof;

FIG. 5 is a right side elevational view thereof;

FIG. 6 is a rear elevational view thereof;

FIG. 7 is a bottom plan view thereof; and,

FIG. 8 is a left side elevational view thereof.
